UNITED STATES PATENT OFFICE.

JAMES H. WHITE, OF NEW YORK, N. Y., ASSIGNOR TO MANHATTAN BRASS COMPANY, OF SAME PLACE.

DESIGN FOR A FENDER.

SPECIFICATION forming part of Design No. 14,170, dated August 14, 1863.

Application filed May 16, 1883. Term of patent 7 years.

To all whom it may concern:

Be it known that I, JAMES H. WHITE, of the city and State of New York, have invented a Design for Fenders, of which the following is a specification.

5 The fender is represented in the perspective view, Figure 1, and the special design of the open-work is represented in larger size in Fig. 2.

10 The rosette ornaments *a* are at intervals, and between them there are the stem and leaflet ornaments *b c*, as represented. These ornaments are in the open-work metal, and extend around the fender in one or two rows. Below 15 the open-work there is a raised band, *d*, diagonally corrugated, as shown.

I claim as my invention—

1. The design of the open-work having the rosette ornaments *a*, with the intermediate stem and leaflet ornaments, *b c*, substantially 20 as represented.

2. The design for a fender, consisting of the ornamental open-work rosettes *a*, leaflets *c*, and stems *b*, and the raised corrugated band *d*, substantially as represented. 25

Signed by me this 7th day of May, A. D. 1883.

JAMES H. WHITE.
